UNITED STATES PATENT OFFICE

145,245

DESIGN FOR A COMBINATION JIGGER AND BOTTLE OPENER

John G. de Lemos, Palo Alto, Calif.

Application September 11, 1945, Serial No. 122,009

Term of patent 14 years

(Cl. D44—29)

To all whom it may concern:

Be it known that I, John G. de Lemos, a citizen of the United States and a resident of the city of Palo Alto, county of Santa Clara, State of California, have invented a new, original, and ornamental Design for a Combination Jigger and Bottle Opener, of which the following is a specification, reference being had to the accompanying drawing, forming a part thereof.

Fig. 1 of the drawing is a perspective view of the combination jigger and bottle opener shown substantially vertical and showing the upper end of the jigger closed by a screw closure cap and with a cork screw folded into a recess in the outer wall of the jigger, all showing my new design.

Fig. 2 is a reduced scale view of the combina-

tion jigger and bottle opener showing the opposite side to that shown in Fig. 1 and with portions of the front wall of the device broken away and showing the cap unscrewed from the upper end exposing the open mouth and interior of the jigger, and with the cap screwed into a threaded depression in the bottom of the jigger and showing the extending bottle cap remover and ice pick which are attached to the cap and which normally extend into the jigger space when the cap closes the same as in Fig. 1.

I claim:

The ornamental design for a combination jigger and bottle opener, substantially as shown and described.

JOHN G. DE LEMOS.
